GAS ANALYSIS APPARATUS

Alfred B. Costello, Niagara Falls, N. Y.

Application October 25, 1939, Serial No. 301,277

4 Claims. (Cl. 23—256)

This invention relates to testing apparatus more particularly adapted for determining the percentage of carbon dioxide (CO_2) in the products of combustion in furnaces, kilns, gas producers and other apparatus.

Further objects of the invention are to provide testing apparatus in which the incoming gas cannot contact with wet walls of the apparatus, to provide an inclined reading tube to promote easier reading, to provide a compact device, without accessories, for making a great number of tests in less time than previous apparatus, and to provide apparatus of this type which is conveniently portable.

A further object is to provide apparatus of this character which will be formed of a few strong simple and durable parts which will be inexpensive to manufacture and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming part of this specification—

Figure 1 is a front elevation of the apparatus in normal position.

Figure 2 is a side elevation of the apparatus shown in Figure 1.

Figure 3 is a front elevation of the apparatus tilted anti-clockwise.

Figure 4 is a plan view of the movable top member of the control valve showing the passages thereof.

Figure 5 is a plan view of the stationary bottom member of the valve showing the ports thereof.

Figure 6 is a diagrammatic view of the valve in neutral position.

Figure 7 is a diagrammatic view of the valve in position to receive a sample.

Figure 8 is a diagrammatic view of the valve in absorption position.

Figure 9 is a diagrammatic view in reading taking position.

Figure 10 is a cross sectional view of an auxiliary valve located between the control valve and sample entrance tube.

Figure 11 is a view similar to Figure 10 showing the valve in a different position.

Referring now to the drawing in which like

characters of reference designate similar parts in the various views, 10 designates a revolute frame which may be simply a board having at the top and bottom thereof flanges 11 and 12, the latter forming a support upon which the frame may be disposed in vertical position in both sample receiving position and in the CO_2 measuring position. The frame may be rotated anti-clockwise through an angular advance of 90° , as shown in Figure 3, to absorption position.

Mounted on the frame, in an inclined position of about 45° to the horizontal, is a burette 13 having a scale 14 disposed longitudinally thereof. The scale is secured to the burette near the opposite ends by strap brackets 15 and 16.

One end of the burette communicates with a reservoir 17 and the opposite end of the burette also communicates with a reservoir 18 both extending from the same side of the burette at a substantially right angle thereto and in which a mercury supply 19 may be interchangeably received as the apparatus is tilted from the position shown in Figure 1 to the position shown in Figure 3, to form a mercury pump.

An absorption chamber 20 is disposed on the frame 10 in a position to pass across and underneath the burette and scale at substantially a right angle, and is secured to the frame by a strap bracket 21. The absorption chamber may be any suitable CO_2 absorption chamber used for the purpose of analyzing exhaust gases.

Disposed in the absorption chamber is a bubbling tube 22 which extends longitudinally of the chamber to the bottom thereof and the absorbent 35 is prevented from entering the bubbling tube through the medium of a mercury seal 23. A neck 24 is formed on the absorption chamber and is closed by a plug 25 to permit cleaning and refilling of the absorption chamber.

A control valve 26 is mounted on the base near the top thereof, as best shown in Figure 1, and comprises an upper revolute member 27 and a lower stationary member 28. The upper member is provided with a hand lever 29 which terminates in a pointer 30. The pointer is movable over a scale 31 fixed to the upper flange 11 and marked with letters "S," "R," "A," "N," for respectively denoting "sample," "reading," "absorption," and "neutral" positions of the valve. The upper member is rotatably mounted on the lower member through the medium of a pin 32 and a helical spring 33 is confined under tension between a nut 34 on the pin and the top of the upper member 27 of the valve to hold the valve in adjusted positions.

The sample to be tested may be taken from a flue 35 through the medium of a tube 36 which is secured to the base 10 and is connected to a pipe 37 which is controlled by a four-way stopcock 38, as best shown in Figures 10 and 11. The stopcock permits a sample being run through the absorption chamber 20 more than once before being released into the atmosphere. The stopcock is provided with a radial passage 39 which communicates with an axial passage 40 which opens into the atmosphere. The stopcock is also provided with a circumferential passage 41 adapted to cross connect a pipe 42 with the gas admitting pipe 37 or to cross connect the pipe 42 with a pipe 43.

The pipes 42 and 43 open through the bottom member of the control valve 26. A pipe 44 is connected at one end to the outer end of the reservoir 19 and at the other end opens through the bottom member of the control valve 26. A pipe 45 is connected at one end to the outer end of the reservoir 18 and opens at the other end through the bottom member of the control valve. A pipe 46 is connected at one end to the top of the bubbling tube 22 and opens at the other end through the bottom member of the control valve. A pipe 47 is connected at one end to the end of the absorption chamber near the outlet end of the bubbling tube and opens at the other end through the bottom member of the control valve. The upper member 21 of the control valve is provided with a pair of arcuate passages 48 and 49 adapted to connect these pipes in a predetermined sequence in making a test as will now be described.

The control valve is in the position shown diagrammatically in Figure 7, and the stopcock is in the position shown in Figure 10, and the base 10 is in the position shown in Figure 1 when a sample is being taken. The valve handle is first turned to "S". The arcuate passage 48 of the control valve then connects the pipes 42 and 44 so that the sample from the flue may pass into the pipe 44 above the mercury in the reservoir 19. At the same time, the arcuate passage 49 connects the pipes 45 and 43 so that atmospheric pressure may enter the pipe 45 and the reservoir 18. With the valves set as above described, the base 10 is now rotated clockwise through an angle of 45° to the position shown in Figure 3. The mercury runs down into the reservoir 18 and pumps the sample into the reservoir 19 and pipe 44.

After the sample is thus pumped into the reservoir 19, the next step is to pump the sample out of the reservoir 19 into the absorption chamber 20. To accomplish this the valve handle is turned to "A," so that, as shown in Figure 8, the arcuate passage 48 connects the pipes 44 and 46 and the arcuate passage 49 connects the pipes 47 and 45. Then the base 10 is turned anti-clockwise through an angle of about 45°. The mercury then runs back into the reservoir 17 again, as shown in Figure 1, and pumps the sample from the reservoir 17, through the pipe 44, pipe 45, bubbling tube 22, and through the mercury seal 23 in the absorption chamber 20.

After absorption has taken place, the next step is to take a reading. To accomplish this the apparatus is held steady in the position shown in Figure 1 and the valve handle is turned to "R" position. In this position of the valve, as shown in Figure 9, the arcuate passage 48 connects the pipes 42 and 44 and the arcuate passage 49 connects the pipes 47 and 45. A vacuum

is created in the absorption chamber through the absorption of CO₂ by the caustic solution in the chamber during the passage therethrough of the gases. The stopcock is now turned to the position shown in Figure 2 to dispose the radial air vent 39 in registration with the pipe 42. Vacuum exerted through the pipes 47 and 45, reservoir 18, and burette 13 coacts with air pressure through the pipes 42 and 44 exerted upon the mercury in the reservoir 19, to cause the mercury to rise in the burette 13 so that a reading may be taken on the scale 14.

Figure 6 shows the "neutral" position of the control valve. In this position the arcuate passage 48 is only connected to the pipe 47 which extends to the absorption chamber 20, and the arcuate passage 49 is only connected to the pipe 46 which is connected to the bubbling tube 22.

To send a sample through the absorption chamber a second or third time, the stopcock 38 is turned to the position shown in Figure 11 so that the circumferential passage 41 connects the pipes 42 and 43 and the operations above described are continued through another cycle.

In lieu of mercury, color solutions may be used. The gas absorbent used corresponds to the gas to be analyzed, such as KOH for CO₂. The reading scale 22 is calibrated to suit the gas to be tested.

By referring to Figure 2, it will be seen that the tube 36 is rigid and forms an axis of rotation for the base 10 so that the apparatus may be operated quickly while attached to the flue 35 and thus a greater number of tests may be made in less time than ordinarily can be made. This time saving advantage is also promoted because the device is light and compact and therefore easily portable to be applied selectively to any number of flues or the like.

From the above description it is thought that the construction and operation of the invention will be fully understood without further explanation.

What is claimed is:

1. A portable apparatus for testing products of combustion for carbon dioxide, comprising a rotatable base, a burette extending at an angular inclination across the base substantially 45° to the horizontal, an absorption chamber extending across the burette substantially at a right angle thereto, a scale disposed longitudinally of the burette, reservoirs at the opposite ends of the burette, a liquid interchangeably receivable in the reservoirs when the base is rotated forward and backward through an arc of about 90° from its initial position to form a pump, a bubble pipe in the absorption chamber, a liquid seal in the absorption chamber in which the end of the bubble pipe is submerged, a control valve, and respective pipes connecting both of the reservoirs, the bubble pipe, the absorption chamber and the atmosphere with the control valve, a tube projecting through the base for conducting gas to be treated to the control valve, said control valve having a rotatable part adapted to connect said pipes in predetermined sequence, the arrangement being such that at one setting of the valve the base may be rotated clockwise from its initial position to suck said gas into one of the reservoirs, at another setting of the valve the base may be rotated anti-clockwise back to its initial position to expel the gas through the bubble pipe into the absorption chamber, and at another setting of the valve atmospheric pressure is admitted on top of the

liquid in the lowermost reservoir to coact with the vacuum created in the other reservoir and in the burette by absorption in the absorption chamber and cause the liquid to rise in the burette so that a reading may be obtained on said scale.

2. The structure as recited in claim 1 but in which the pipe connecting the control valve to the atmosphere includes a stopcock adapted also to return tested gas a plurality of times to the control valve for retesting, in addition to connecting the control valve to the atmosphere.

3. The structure as recited in claim 1 but in which the tube which conducts gas to be treated to the control valve is rigid and forms an axis of rotation for the base when the tube is inserted in a flue from which gas is to be tested.

4. The structure as recited in claim 1 in which the control valve is provided with a rotary part associated with a handle lever forming a pointer movable over a dial bearing characters indicating various settings of the control valve.
